PERRY OKEY, OF COLUMBUS, OHIO, ASSIGNOR TO W. H. LALLEY, OF DETROIT, MICHIGAN.

GAS-ENGINE GOVERNOR.

1,202,210.

Specification of Letters Patent. Patented Oct. 24, 1916.

Application filed December 9, 1910. Serial No. 596,408.

To all whom it may concern:

Be it known that I, PERRY OKEY, a citizen of the United States, residing at Columbus, in the county of Franklin and State of Ohio, 5 have invented certain new and useful Improvements in Gas-Engine Governors, of which the following is a specification.

This invention relates to engine governors of the electric type and has particular application to various forms of engines used in connection with electric generators.

Various types of governors have been devised for throttling the engines driving a generator, but these governors have, in practically all instances, been designed to create a state of stability or equilibrium. These devices have met with varying amounts of success, but they are particularly undesirable for use in connection with internal combustion engines, as there are so many features which enter into their operation which tend to vary the out-put thereof. These are brought about by many causes, such as sufficient or insufficient lubrication, quality of the lubricant, temperature of the cooling medium, or of the atmosphere, variation in the ignition from numerous causes, changes in the quality and quantity of the fuel, changes of the humidity or barometrical pressure of the air, or any combination of these and many others. Any of these may result in an engine operating on a constant load to increase or decrease its speed. It will, therefore, be apparent that electric governors, particularly those governed by the voltage of the generator, must be efficient, as these features are not under their control. Therefore, my invention resides in the provision of a governor which does not intend to establish a state of equilibrium, but on the contrary, is what I have termed of the unstable type. This governor is used in connection with the throttling valve of an engine and my main object resides in the provision of means for continuously moving the valve between the position of greater and less opening than the load requirement for the same condition of external load. In other words, the valve of the engine is at all times fluctuating between a position of greater and less opening than the load requirement and consequently a balance is effected between these two positions to constantly maintain the out-put of the generator uniform for any given load requirement. By the same position for a given load re-

quirement is not meant that the external load is constant at all times, for it is very evident that it may be varied between any desired limits and as frequently as is practical, but construction is employed so that the fluctuating of the valve takes place at all times whether the load requirement is such that the opening of the valve is one-quarter of an inch to effect the balance necessary, or whether it is three-quarters of an inch.

Further, another object of my invention resides in so constructing the fluctuating mechanism that its operation is more rapid than the ordinary variations or fluctuations of an external load. Therefore, these rapid fluctuations of the controlling valve both above and below the requisite opening for the applied load effects the nicety of balance necessary to give the required governing effect.

The above objects are preferably accomplished by the provision of a potential relay sensitized to such a degree that minute variations in the potential of the working circuit will cause its operation. The preferred way of using this potential relay is with electric actuating mechanism for opening the valve more than is necessary for the load requirement and having a second electric actuating mechanism which closes the valve more than is necessary for the load requirement, the relay coming into play to so control these mechanisms that the valve is continually fluctuated as outlined. In other words, when the valve is closed too far, a decrease in speed is the result and this decrease reduces the voltage generated. However, this decrease is only momentary and then the valve moves to such a position that an excess speed is had which increases the voltage. The relay mentioned is so constructed that a very small variation in the voltage will cause its operation one way or the other, that is, to either cause the actuating mechanism to open or close the valves.

The preferred embodiment of my invention is shown in the accompanying drawings, in which similar characters of reference designate corresponding parts, and in which: the numeral 5 designates a gas engine of any ordinary or well known type and 6 indicates the dynamo driven thereby. The fuel intake pipe 7 leading to the cylinder of the engine, is divided into two chambers, 8 and 9, communicating with each other through a

suitable opening 10, the discharge through the mixing valve 11 entering the chamber 9 immediately below the air inlet tube 11^a.

A line wire 12 is connected to one of the 5 binding posts 13 of the dynamo. The line wire 14 leads from the binding post 16 of the dynamo to one end of the winding of the solenoid 15 and also to one end of the winding of the solenoid 22, through the connection 22^a. The other end of the winding of the solenoid 15 is connected by the wire 14^a to the working circuit, thus causing the current used in the working circuit to pass through the winding of the solenoid 15. In 10 units of large out-put, it may be found desirable to provide a shunt circuit of either variable or fixed resistance, to divert a part of the total current used in the working circuit from the windings of the solenoid 15, 15 and such a shunt is shown at 14^b. The soft iron core 17 forms a part of the valve controlling the area of opening of the ports 10^a, this soft iron core being preferably tubular in form and having an opening 18 therein, 20 in order to avoid any dash-pot effect. This core is also provided with a spring 19. Connected to the upper part of the soft iron core 17, is a valve 20 of brass or other non-magnetic material, said valve in the present instance, being preferably in the form of a piston. The piston valve is set, by means of the spring adjusting nut 21, so that a sufficient area of opening through the ports 10^a is obtained to start the engine and permit 25 the latter to run at a maximum required speed when no load is connected to the dynamo. As the load is added to the working circuit, the series solenoid 15 will draw the soft iron core and consequently the piston 30 valve downward to such an extent as will permit a slight excess of gaseous mixture to be supplied to the engine, which causes the voltage of the dynamo to rise above the normal. Mounted above the series solenoid and 35 acting in opposition thereto, is a second solenoid 22, which tends to close the valve against the action of the series solenoid when actuated as follows:

29 designates a relay magnet, the windings of which are permanently connected 40 across the working circuit, said magnet having a core 30 thereof carried by the armature bar 31 pivoted at 32 to the base plate 33, a spring 34 normally tending to draw 45 this armature bar upwardly. The contact point 35 is mounted on the end of the armature bar adjacent the contact point 36 carried by an adjusting screw mounted in any desirable manner upon the base plate 33. 50 As stated, the potential relay is connected across the working circuit, this connection being the wires 37 and 38, said relay being also connected through the wire 22^a, and wire 34^a leading from wire 37 to the pivot 55 point 32, with the solenoid 22, so that when

the relay is closed, the latter will be energized and acting in opposition to the series solenoid 15 will tend to draw the valve upwardly and consequently partially close the ports, thereby decreasing the amount of fuel supplied to the engine to a degree not quite sufficient to maintain the necessary speed, thus causing the voltage to drop below the normal. When this occurs, the relay contacts are again opened de-energizing the upper 75 solenoid 22 and permitting the soft iron core piston valve to be again drawn down and opened by the action of the solenoid 15 to a point permitting a slight excess of fuel to be furnished to the engine. These connections being carried on with considerable rapidity, result in the variable charge being taken by the engine, or in other words the governor operates on the throttling principle at all times. 85

It will be noted that I have provided a type of governor wherein, instead of employing a plurality of valves and a plurality of solenoids for actuating the same, I employ but a single valve accurately controlling the 90 passage of fluid to the engine and consequently the speed of the dynamo, said valve being controlled and actuated by a plurality of solenoids acting in opposition one to the other, one of said solenoids being controlled 95 in its action by the potential relay, the latter of which is effected by the rise and fall of the voltage of the dynamo.

What I claim is—

1. In combination with an engine driven 100 dynamo, a throttling inlet valve for said engine, electric means for opening said valve wider than the load requirement, supplemental electric means acting in a direction opposite to said first means and operating to close said valve to a position below the load requirement, and operating means controlling said first two means in a manner so that the valve is either closed too far or open 105 too far under the same condition of external load, said operating means being actuated by the rise and fall of the voltage of the dynamo due to the variations of speed caused by the throttling action. 110

2. In combination with an engine driven dynamo, a throttling inlet valve for said engine, electric means for opening said valve wider than the load requirement, supplemental electric means acting in a direction opposite to said first means and operable to close said valve to a position below the load requirement, and operating means controlled by the voltage generated for alternately rendering one and then both of said first 120 two means effective to alternate the position of said valve as related under the same external load requirement. 125

3. In combination with an engine driven dynamo, a throttling inlet valve for said 130 engine, electric means for opening said valve

- wider than the load requirement, supplemental electric means acting in a direction opposite to said first means and operable to close said valve to a position below the load requirement, and operating means for alternately rendering one of said first two means effective and ineffective for the same condition of external load, the other of said two means being continuously effective, said operating means being controlled by the voltage generated by said dynamo.
4. In combination with an engine driven dynamo, a throttling inlet valve for said engine, electric means for variably holding said valve open to a point greater than that necessary to supply sufficient energy to the engine to carry the dynamo load, and an intermittently operative electric means in opposition to said first means effective to close said valve to a point below that necessary to supply sufficient energy to the engine to carry the dynamo load, said two means causing a continuous alternation of said valve as specified for the same external load.
5. In combination with an engine driven dynamo, a throttling valve for said engine, a solenoid connected in series with the work circuit of said dynamo and having a core connected to said valve, said solenoid tending to open said valve to a position greater than the load requirement, a second solenoid, the windings of which are connected across the work circuit of the dynamo, adapted to work in a direction opposite to said first solenoid to move said valve to a position of closure below the load requirement, and a potential relay connected in the work circuit and operable by a slight variation of voltage for intermittently energizing said second solenoid. 40

In testimony whereof I affix my signature in presence of two witnesses.
